UNITED STATES PATENT OFFICE.

ANDREW E. DELANEY, OF ASHLAND, WISCONSIN.

CARD-HOLDER.

1,361,310.

Specification of Letters Patent. Patented Dec. 7, 1920.

Application filed June 24, 1920. Serial No. 391,367.

To all whom it may concern:

Be it known that I, ANDREW E. DELANEY, a citizen of the United States, residing at Ashland, in the county of Ashland and State of Wisconsin, have invented a new and useful Card-Holder, of which the following is a specification.

It is the object of this invention to provide novel means whereby a card may be held on a car or other support.

In the drawings:—Figure 1 is a front elevation; Fig. 2 is a section on the line 2—2 of Fig. 1; Fig. 3 is a section on the line 3—3 of Fig. 1.

The numeral 1 denotes a portion of a railroad car to which a main frame 2 is connected by bolts 3 or otherwise, the frame preferably being enlarged slightly, at its sides, as shown at 4, to accommodate the bolts. In the top of the main frame 2, intermediate the ends thereof, an opening 5 is formed in the main frame. In the sides of the main frame, near to the top thereof, notches or seats 6 are fashioned.

An auxiliary frame 7 fits within the main frame 2 and rests against the car 1, the auxiliary frame being provided at its upper corners with stub shafts 8 mounted in the notches or seats 6 of the main frame 2. A bar 9 extends across the auxiliary frame 7, one end of the bar being enlarged to form an eye or handle 10. The other end of the

bar 9 projects beyond the top of the auxiliary frame 7 and overhangs the top of the main frame 1, the projecting portion of the bar being broadened as indicated at 11 so that a socket 12 may be formed in the rear surface of the said projecting portion. One end of a compression spring 40 is mounted in the opening 5, the other end of the spring 40 being mounted in the socket 12.

In practical operation, the auxiliary frame 7 may be swung outwardly at its lower end, the frame pivoting on the stub shafts 8, and the spring 20 being put under compression. A card 25 may be slipped under the frame 7, the bar 9 pressing the card against the car 1 when the frame 7 is released, the spring 20 serving to press the frame 7 inwardly against the car. The spring 20 is housed in the socket 12 and in the opening 5 so that practically none of the spring is exposed to the weather.

I claim:—

In a device of the class described, pivotally connected frames located one within the other, the inner frame embodying a cross bar including a projecting portion overhanging the outer frame; and a compression spring interposed between said projecting portion and the outer frame.

In testimony that I claim the foregoing as my own, I have hereto affixed my signature.

ANDREW E. DELANEY.
